UNITED STATES PATENT OFFICE.

FERDINAND W. PECK, OF PENNS GROVE, NEW JERSEY, AND JOHN H. SACHS, OF WILMINGTON, DELAWARE, ASSIGNEES TO E. I. DU PONT DE NEMOURS & COMPANY, OF WILMINGTON, DELAWARE, A CORPORATION OF DELAWARE.

PROCESS OF MAKING BENZANTHRONE AND ITS DERIVATIVES.

No Drawing.

Application filed August 23, 1924. Serial No. 733,839.

This invention relates to the production of benzanthrone and its derivatives, and comprises heating anthracene or one of its derivatives, such as anthranol, with glycerine and a condensing agent in the presence of an oxidizing agent.

The method heretofore generally used in preparing benzanthrone is described in Example 2 of U. S. Patent No. 787859 to R. H. Scholl and O. Bally, according to which anthranol is suspended in sulfuric acid (82% strength), glycerine added, and the mixture heated until the reaction is completed. We have now discovered that this reaction is facilitated and accelerated by the action of an oxidizing agent, and particularly a mild oxidizing agent such as nitrobenzene and anthraquinone. The use of anthraquinone for this purpose is particularly advantageous in view of the fact that in acting as an oxidizing agent, it is reduced to anthranol, which then takes part in the condensation, the introduction of an extraneous material into the reaction mixture being thereby avoided.

The yield of benzanthrone is substantially increased by using an oxidizing agent in accordance with our invention, being in some cases as much as 88% of the theoretical as compared with the 65-70% yield obtainable with the process as heretofore practiced.

According to our preferred method of operating, we start with a given weight of anthraquinone and reduce a portion only of this anthraquinone to anthranol, and then when the reduction has proceeded to the proper ratio of anthranol and anthraquinone begin the condensation. The same results may be obtained by preparing the anthranol separately and mixing this with the proper ratio of anthraquinone. The best results in the way of yields are obtained with 35-40 parts of anthranol to 60-65 parts of anthraquinone, the yield being 85-88%. With 100% anthranol, the yield is around 70% and with anthranol and nitrobenzene the yield is 75-80%.

Aside from the increase in yield obtained by the use of anthraquinone as an oxidizing agent, is the advantage of obtaining a relatively large amount of benzanthrone from a small amount of anthranol. The reduction of anthraquinone to anthranol

is a costly operation; obviously therefore the less anthraquinone that must be reduced the lower the cost of benzanthrone.

Our improved procedure may be illustrated by the following examples:

I. 10 parts of anthranol are dissolved in 220 parts of 95% sulfuric acid and 2 parts of nitrobenzene are added, after which the mixture is warmed to 40° C. and 30 parts of a mixture of 50 parts of water and 50 parts of glycerine are added in the course of one-half hour, the temperature being allowed to rise to 90° C. during this addition. The mixture is then heated in the course of an hour and a half to 12° C. at which point it is maintained for three hours. It is then cooled to 60° C. and drowned in 1000 parts of water. The precipitated crude benzanthrone is filtered off, washed acid free and then boiled up with 500 parts of a 1% solution of caustic soda. The mass is filtered hot, the cake of benzanthrone is washed with hot water until alkali free and is then dried. The yield is 75-80% of the theory.

II. A mixture of 6 parts of anthraquinone and 4 parts of anthranol are dissolved in 220 parts of 95% sulfuric acid at room temperature. The mixture is warmed to 40° and at this point the addition of 30 parts of a mixture of 50 parts of water and 50 parts of glycerine is begun. The procedure from this point is similar to that in Example I.

III. 10 parts of anthraquinone are dissolved at room temperature in 220 parts of 95% sulfuric acid and the solution is warmed to 40° C. Aluminum powder is then added until a test portion shows that 40% of the anthraquinone has been reduced. For this amount of reduction approximately 2 parts of aluminum are required. The addition of 30 parts of a mixture of 50 parts of water and 50 parts of glycerine is then begun. The procedure from this point is similar to that in Example I.

In place of anthraquinone in the above examples, various other substances having a moderate oxidizing action may be used, but we prefer anthraquinone for the reason stated above. Other conditions specified in Example I above, such as durations of the reaction periods, and temperatures employed, may of course be varied to a certain

extent without departing from our invention.

We claim:

1. The process of producing benzanthrone which comprises condensing an anthracene compound free from nitrogen with glycerine in the presence of an oxidizing agent.
2. The process of producing benzanthrone which comprises condensing anthranol with glycerine in the presence of an oxidizing agent.
3. The process of producing benzanthrone which comprises condensing anthranol with glycerine in the presence of sulfuric acid and of an oxidizing agent comprising anthraquinone.
4. The process of producing benzanthrone which comprises heating an anthranol compound with glycerine and strong sulfuric acid in the presence of an oxidizing agent.
5. A process as defined in claim 4 in which the oxidizing agent is anthraquinone.
6. A process as defined in claim 4 in which the oxidizing agent is an aromatic compound having a mild oxidizing action.
7. The process of making benzanthrone which comprises heating, eventually to about 120° C., a mixture containing anthranol, glycerine, sulfuric acid, and anthraquinone, and recovering the benzanthrone resulting from the reaction thus induced.
8. The process of producing benzanthrone which comprises heating a mixture containing sulfuric acid, glycerine, four parts of anthranol, and about 6 parts of anthraquinone, and recovering benzanthrone resulting from the reaction thus induced. 85
9. A process as defined in claim 8 in which the mixture is heated to a temperature of about 120° C. for about 3 hours. 90
10. The process of making benzanthrone which comprises dissolving four parts of anthranol and about six parts of anthraquinone in about 220 parts of 95% sulfuric acid, gradually adding about 30 parts of a mixture of about equal parts of water and glycerine to the sulfuric acid solution at a temperature ranging from 40° C. at the start to about 90° C. when the addition of glycerine is completed, heating the resulting mixture at a temperature above 90° C. but below that at which undesirable decomposition of the reagents would occur, until the conversion of anthranol to benzanthrone is practically completed, cooling the mass, 55 drowning it in water, and filtering and washing the precipitate.

In testimony whereof we affix our signatures.

FERDINAND W. PECK.
JOHN H. SACHS.

extent without departing from our invention.

We claim:

1. The process of producing benzanthrone which comprises condensing an anthracene compound free from nitrogen with glycerine in the presence of an oxidizing agent.
2. The process of producing benzanthrone which comprises condensing anthranol with glycerine in the presence of an oxidizing agent.
3. The process of producing benzanthrone which comprises condensing anthranol with glycerine in the presence of sulfuric acid and of an oxidizing agent comprising anthraquinone.
4. The process of producing benzanthrone which comprises heating an anthranol compound with glycerine and strong sulfuric acid in the presence of an oxidizing agent.
5. A process as defined in claim 4 in which the oxidizing agent is anthraquinone.
6. A process as defined in claim 4 in which the oxidizing agent is an aromatic compound having a mild oxidizing action.
7. The process of making benzanthrone which comprises heating, eventually to about 120° C., a mixture containing anthranol, glycerine, sulfuric acid, and anthraquinone, and recovering the benzanthrone resulting from the reaction thus induced.

8. The process of producing benzanthrone which comprises heating a mixture containing sulfuric acid, glycerine, four parts of anthranol, and about 6 parts of anthraquinone, and recovering benzanthrone resulting from the reaction thus induced.

9. A process as defined in claim 8 in which the mixture is heated to a temperature of about 120° C. for about 3 hours.

10. The process of making benzanthrone which comprises dissolving four parts of anthranol and about six parts of anthraquinone in about 220 parts of 95% sulfuric acid, gradually adding about 30 parts of a mixture of about equal parts of water and glycerine to the sulfuric acid solution at a temperature ranging from 40° C. at the start to about 90° C. when the addition of glycerine is completed, heating the resulting mixture at a temperature above 90° C. but below that at which undesirable decomposition of the reagents would occur, until the conversion of anthranol to benzanthrone is practically completed, cooling the mass, drowning it in water, and filtering and washing the precipitate.

In testimony whereof we affix our signatures.

Certificate of Correction.

It is hereby certified that in Letters Patent No. 1,601,319, granted September 28, 1926, upon the application of Ferdinand W. Peck, of Penns Grove, New Jersey, and John H. Sachs, of Wilmington, Delaware, for an improvement in "Processes of Making Benzanthrone and its Derivatives," an error appears in the printed specification requiring correction as follows: Page 1, line 69, for "12° C." read 120° C.; and that the said Letters Patent should be read with this correction therein that the same may conform to the record of the case in the Patent Office.

Signed and sealed this 12th day of October, A. D. 1926.

[SEAL.]

M. J. MOORE,
Acting Commissioner of Patents.
